Primary Examiner — Jennifer L Watkins*Assistant Examiner* — Christine TucciCLAIM

The ornamental design for a shoe, as shown and described.

DESCRIPTION

FIG. 1 is a front, top perspective view of a shoe, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the shoe that form no part of the claimed design.
